DOUBLE SEALING TOOL

Original Filed July 20, 1921

UNITED STATES PATENT OFFICE

BENONI NOWLAND, OF PHILADELPHIA, PENNSYLVANIA, ASSIGNEE, BY MESNE ASSIGNMENTS, TO SIGNODE STEEL STRAPPING COMPANY, A CORPORATION OF DELAWARE

DOUBLE-SEALING TOOL

Refiled for abandoned application Serial No. 486,057, filed July 20, 1921. This application filed June 22, 1923. Serial No. 647,163.

My invention relates to that class of sealing tools in which a sleeve or shield of flexible or pliable material is folded around the meeting ends of flat box-strapping and 5 pressed or otherwise forced into gripping contact with said strapping so as to form a seal capable of resisting the various strains to which said strapping may be subjected during transportation.

10 The object of my invention is to provide a simple, strong and effective tool for the above purpose, which has the added feature of making a double or two-part sealing of the shield to the strapping by a single operation of the tool,—each of said sealing connections being independent of the other and each, capable alone of holding the strapping against its ordinary strains. In other words I afford double protection against displacement of the strapping during transportation.

15 The present application is a substitute for my prior application, Serial No. 486,057, filed July 20, 1921.

To this end my invention consists, broadly, 20 of a pair of independent plunger dies, operating from the same fulcrum, under control of a pair of cam levers which may be operated together or separately as preferred to move their respective plunger dies.

25 In the accompanying drawings I have shown my invention in a form especially adapted to making the type of seal shown in Figure 6 but it will be readily understood that my double sealing tool may be varied 30 quite largely in details of construction to produce other types of seals without in any way departing from the principle of my invention.

In these drawings:—

35 Figure 1, is an end elevation, as it were, the tool being laid on its side.

Figure 2, is a lateral elevation.

Figure 3, is a vertical section on line 3—3 of Figure 2.

40 Figure 4, is a vertical section on line 4—4 of Figure 1.

Figure 5, is a detail of the plunger and the intermediate roller which plays between said plunger and the operating cam-lever.

45 Figures 6, and 7 are details of two meet-

ing ends of box-strapping sealed by my improved double sealing tool.

Reference may now be had to the drawings in which similar letters of reference indicate like parts in the different figures.

55 A, is the part which may be called the body, or housing, or frame of the tool, being that portion on which the two cam levers, B, C, are mounted, and in which the two loose rolls, D, D,—the two plungers, E, E,—and the single fulcrum or pivot pin F, are located and have their field of operation. All of these parts are strong, durable, and of simple and economic construction.

60 G, is a type of sleeve of flexible or pliable metal folded around the strap ends H, H, to make the seal as is customary.

65 The above five parts are the important parts of my improved tool. Each of them has, as shown in the drawings minor features which may be varied according to circumstances or convenience. For example:—

70 The body portion A, is preferably made, as shown, as a casting terminating in a foot or rest plate a, adapted to rest on the box or other article to be strapped and having insets or bottom dies b, b, against which the plunger points come to make the seal required. Grooves c, c, are provided in dies b, b to allow for part of the material of the 75 seal to be forced downwardly therein by the descending plunger points. The interior of this body A, is provided with guideways in which plungers E E reciprocate and is further shaped so that the cam-levers and other 80 movable parts can operate freely as required. It is also preferably provided with a face plate d, held by screws, e, e, to close the side 85 of this open interior.

86 The cam-levers B, C, consist primarily of two parts, the cams or cam-heads f, f', and the handles, g, g'. These two levers are loosely mounted upon the single fulcrum pin, F, which is journaled in the body A, and they face in opposite directions, preferably, so 90 that the swinging of the two levers into a closed position, like scissors, causes the plungers to move downward and make the seal,—while the spreading or swinging open 95 of the two levers lifts the plungers back to 100

their normal position, and frees the sealed strapping. The loose rolls D, D, serve not only as a sort of ball bearing for the cam-heads but protect the upper surface of the plunger block h, from undue wear. The levers lift the plungers by coming up against the underside of the flanges i, i. The side portions of the plungers E are slotted at E' to receive the fulcrum pin F which extends through both plungers.

The plungers E, E, are preferably provided with points or punches j, j, of a size and shape adapted to form the particular type of seal required. The special points shown in the drawings are adapted to make the depressions k, k, of Figures 6 and 7.

When employing the tool for sealing together the ends of box strapping, the bottom surface a' of frame member A is in engagement with the face of the package or box which is being strapped. It will be seen that immediately above the foot a, a slot a² is provided substantially parallel with the bottom surface a', said slot furnishing means whereby the metal strapping may be inserted within reach of the die portions of the sealing tool. The plungers E being advanced downwardly by means of the shoulders or cam heads f' bearing against the rollers D and raised by a portion of the same surface bearing against the undersides of the flanges i, i, operation of the two cam levers or handles B and C will function to reciprocate the plungers within the frame member or more specifically within the guideways provided for the plungers within said frame member.

The two plungers move in separable relation, each one being actuated by one of the levers B or C. Each one of the plungers carries its own die or deforming member which co-operates with the lower die or complimentary deforming surface in the foot a.

The usual method of sealing strapping can be adopted when employing my tool the practice being to bring the two ends of the strap together in overlapping relation, placing a metal sleeve around the overlapping strap ends and inserting the assembled overlapping strap ends and sleeve within the slot as A² so that the bottom surface of the tool is in engagement with the package being strapped. Pressure is then applied to bring the two handles together, thereby crimping the metal surfaces of the joint in the manner shown in the drawings.

What I claim as new and desire to protect by Letters Patent is as follows:

1. In a portable sealing device, the combination of a frame member having a slot therein extending substantially parallel to the bottom surface of said frame member and defining a narrow foot for slipping under the strapping, guideways in opposite sides of said frame member, two plungers reciprocable in said guideways, deforming

surfaces on said plungers adapted to co-operate with deforming surfaces on said foot, a roller associated with each of said plungers, two levers each pivotally mounted on said frame member for independently actuating said two plungers, each of said levers comprising a cam adapted to bear against the roller on its respective plunger, said levers both extending upwardly from said frame member substantially at right angles to said slot and to the bottom surface of said frame member, said levers operating to advance said plungers toward the bottom surface of the frame member by being squeezed together, and means co-operating with said levers for positively retracting said plungers when said levers are separated.

2. In a portable sealing device, the combination of a frame member having a slot therein extending substantially parallel to the bottom surface of said frame member and defining a foot for slipping under the strapping, two plungers reciprocable in said frame member, deforming surfaces on said plungers adapted to co-operate with deforming surfaces on said foot, two levers each pivotally mounted on said frame member for independently actuating said two plungers, each of said levers comprising a cam adapted to bear against a portion of its respective plunger, said levers both extending upwardly from said frame member substantially at right angles to said slot and to the bottom surface of said frame member, said levers operating to advance said plungers toward said foot by being squeezed together, and means co-operating with said levers for positively retracting said plungers from said foot when said levers are separated.

3. In a double sealing tool, the combination of a frame having a foot adapted to be inserted between a package and strapping encircling the package, a pair of parallel plungers reciprocably mounted in said frame, each of said plungers having a plane surface parallel with said foot, rollers resting upon said plane surfaces, and a pair of handle levers pivoted to said frame, each of said handle levers having cams adapted to engage said rollers whereby movement of said levers toward each other causes the plungers to move toward said foot by forces exerted upon the movement of said cams through said rollers.

4. In a double sealing tool, the combination of a frame having a foot adapted to be inserted between a package and strapping encircling the package, a pair of parallel plungers reciprocably mounted in said frame, each of said plungers having a plane surface parallel with said foot, rollers resting upon said plane surfaces, and a pair of handle levers pivoted to said frame, each of said handle levers having cams adapted to engage said rollers whereby movement of

said levers toward each other causes the plungers to move toward said foot by forces exerted upon the movement of said cams through said rollers, said plungers each having portions formed to engage said cams at opposite sides from their points of engagement with said rollers to cause said plungers to be elevated upon the movement of said handle levers away from one another.

10 5. A sealing tool comprising a plurality of manually operable levers, a plurality of plungers, a punch for each plunger, a die adapted to co-act with the punches on said 15 plungers, means for transmitting force from one of said levers to one of said plungers, independent means for transmitting force from a second lever to a second plunger, said means and levers being so disposed with relation to each other that when the levers are grasped simultaneously, one lever and means acts as a point of reaction against the force applied to the other lever and the 20 plungers are independently actuated.

25 6. A sealing tool comprising a plurality of manually operable levers, a plurality of plungers, a punch for each plunger, a relatively stationary die adapted to co-act with the punches on said plungers, means for transmitting force from one of said levers to one of said plungers, independent means for transmitting force from a second lever to a second plunger, said means and levers being so disposed with relation to each other 30 that when the levers are grasped simultaneously, one lever and means acts as a point of reaction against the force applied to the other lever and the plungers are independently actuated.
